SHOE SUPPORT

Archie B. Cornelius, Davenport, Iowa

Application August 17, 1934, Serial No. 740,236

3 Claims. (Cl. 12—128.1)

The present invention relates to apparatus for use in shining shoes or removing dust therefrom. Among the objects of this invention are to provide a shoe-supporting bracket for the purpose indicated which is simple and inexpensive to manufacture; to provide apparatus of the character indicated which is easy to manipulate; to provide apparatus of the character indicated which may be readily mounted upon a wall or other structure in basement, kitchen, bath room, or wherever else it may be desired to place the same; to provide apparatus of the character indicated which is easy to put in place on a wall or remove same therefrom when the work is completed; to provide apparatus of the character indicated such that a shoe may be readily mounted in place thereon or removed therefrom; to provide a structure of the character indicated which will efficiently hold a shoe in place and support the upper thereof for shining purposes; and such further objects, advantages, and capabilities as will hereafter appear and as are inherent in the construction disclosed herein. My invention further resides in the combination, construction, and arrangement of parts illustrated in the accompanying drawing and, while I have shown therein what is now considered the preferred embodiment of this invention, I desire the same to be understood as illustrative only and not to be interpreted in a limiting sense.

In the drawing annexed hereto and forming a part hereof,

Fig. 1 illustrates a plan; Fig. 2, a side elevation; and Fig. 3, an underside view of a construction embodying my invention;

Fig. 4 represents a cross section taken substantially along the plane indicated by the line 4—4, Fig. 2.

Reference will now be made in greater detail to the annexed drawing for a more complete description of this construction which comprises, essentially, a supporting bracket for the shoe and a supporting member for the shoe-upper to hold the same in place while the shoe is being polished. The bracket has a top 1 and turned-down sides 2. It also comprises turned-in flanges 3 and 4 to which is secured an end plate 5 provided with slots for the reception of the screws 6 which are screwed into a wall and upon which the bracket is supported while in use. The top 1 is slotted, as indicated at 7, and provided with openings 8 for the reception of a hook 9 on one end of the spring 10. This plurality of openings 8 provides for adjustment of the spring 10 and the block

11 to which the second end 12 of the spring is connected.

At one end, the bracket is provided with a pair of abutments 13 which are somewhat hook-shaped in order to engage over the top of the sole and hold the same down, as well as preventing movement of the shoe forwardly under the influence of the spring 10. As indicated above, the second end 12 of the spring 10 is connected to the block 11. To effect this connection, a bracket 14 is formed integrally with or connected to the block 11, the same being notched upon opposite sides, as shown in Fig. 4, for the reception of the parts of the top 1 upon opposite sides of the slot 7. As is apparent from the drawing, the bracket 15 is provided with an opening for the reception of the hook 12 of spring 10. The bracket 14 serves as a guide for one side of the block 11, the other side being guided by the bracket 15 on the opposite edge of the block. As shown in Fig. 3, this bracket 15 is much shorter than the bracket 14 and overlaps the sides of the slot 7 much less than is true of the bracket 14. The purpose of making this bracket small is for the sake of ease of assembly when the parts are being put together.

In order to support the shoe-upper in the vicinity of the toe and instep, I provide a bent steel-spring 17 having a bent cross-strip 18 secured thereto. The construction and operation of this will be obvious from Figs. 1 and 2. In order to take care of shoes of different sizes, I may provide two or more of these springs or instep-supports for use with men's, women's, and children's shoes. As indicated above, the openings 8 are for the purpose of adjusting the opening between the holding devices 13 and 16 to take care of shoes of different sizes. How this is accomplished will be obvious without further description. The shoe may be placed with either heel or toe against the abutments 16 and then shoved until the other end can be put inside the abutments 13. In doing this, tension is placed upon the spring 10 and this causes the abutments 13 and 16 to rigidly hold the shoe in place. The spring 17 is then inserted into the shoe so that the upper of the shoe will be supported in place to be polished. After the work has been completed, the bracket can be lifted and the openings in the plate 5 freed from the screws 6, thus permitting the bracket to be put away in storage position.

It will of course be understood that the specific description of structure set forth above may be departed from without departing from the spirit

of this invention as set forth in this specification and the appended claims.

Having now described my invention, I claim:

1. A shoe-holder for shoe-shining purposes, comprising a bracket having openings whereby the bracket may be detachably mounted upon a wall or other support, said bracket having a fixedly mounted projection or projections for engaging externally the toe end of the shoe sole, and 10 a heel-engaging projection slidably mounted on and resiliently actuated along the bracket.
2. A shoe-holder for shoe-shining purposes, comprising a bracket having openings whereby the bracket may be detachably mounted upon a wall or other support to project therefrom at a 15 right angle thereto, said bracket having a fixedly mounted shoe-toe-engaging projection or projections, a heel-engaging projection mounted on the bracket and having a part projecting 20 through a slot in the bracket for the attachment thereto of a spring whereby the projection may be pulled longitudinally of the bracket, and a

spring attached at one end to the bracket and at its other end to the heel-engaging projection.

3. A shoe-polishing holder comprising a bracket having an end whereby the bracket may be detachably secured to a support, a top connected 5 to said end, flanges connecting the top and end to make a rigid structure, said top having a longitudinal slot for the reception and guiding of a holding member, a holding member mounted on said top and having guiding parts extending into 10 said slot, said holding member having parts adapted to engage a part of a shoe and to cooperate with other holding members in holding the shoe in position, other holding members on the top to engage the shoe and cooperate in holding same in position, and resilient means actuating the first named holding member toward the second named holding members to cause gripping of the shoe whereby to hold same in place on the bracket. 15

20 ARCHIE B. CORNELIUS.
